BIOLOGICAL SCIENCE LABORATORY UNIT FOR CLASSROOMS AND THE LIKE

James D. Graham, Manitowoc, Wis., assignor to Hamilton Manufacturing Company, Two Rivers, Wis., a corporation of Wisconsin

Filed Nov. 23, 1962, Ser. No. 72,590

Term of patent 14 years

(Cl. D16—2)

FIG. 1 is a perspective view showing the front, top, and one side of a biological science laboratory unit for classrooms and the like embodying my new design; and

FIG. 2 is a perspective view of the back, top, and the side of the biological science laboratory unit for classrooms and the like not shown in FIG. 1.

The dominant features of my design reside in the portions shown in full lines in the drawing.

The broken line disclosure of the lamp is shown for illustrative purposes only.

I claim:

The ornamental design for a biological science laboratory unit for classrooms and the like, substantially as shown and described.
